UNITED STATES PATENT OFFICE.

WILLIAM C. WHITE, OF SCHENECTADY, NEW YORK, ASSIGNOR TO GENERAL ELECTRIC COMPANY, A CORPORATION OF NEW YORK.

WIRELESS SIGNALING SYSTEM.

Application filed August 23, 1915. Serial No. 46,769.

My present invention relates to signaling systems and more especially to means for transmitting wireless signals.

One of the objects of my invention is to 5 provide means for producing continuous electrical waves and means for varying the amplitude of the waves thereby produced. A more particular object of my invention is to provide means for varying the amplitude of the continuous waves in accordance 10 with variations in sound waves.

In carrying my invention into effect I preferably employ an electron discharge device for producing continuous electrical waves in 15 an antenna. If such a device is supplied with a direct current source of constant potential and suitable circuit connections made thereto it may be made to produce continuous electrical waves of practically 20 constant amplitude in the antenna. If, however, the potential supplied thereto is variable the amplitude of the waves produced will vary in accordance with the potential variations in the source of supply. Hence 25 if the potential of the supply source is caused to vary in accordance with variations in sound waves the amplitude of the waves produced may be caused to vary accordingly.

The features of my invention which I believe to be novel are set forth with particularity in the appended claims. The invention itself, however, with further objects and advantages will best be understood by reference to the following description taken 30 in connection with the accompanying drawing in which Fig. 1 illustrates diagrammatically one way in which my invention may be carried into effect, and Figs. 2 and 3 show modifications thereof.

As indicated in the various figures of the drawing the means for producing continuous electrical waves in the antenna 1 comprises an electron discharge device 2 consisting preferably of a highly evacuated envelope having therein a cathode 3 of filamentary form, an anode 4, and a conducting body 5, which is preferably in the form of a grid, interposed between the cathode and anode. The cathode and anode in the modifications 40 shown in Figs. 1 and 2 are connected respectively to conductors 6 and 7, which in turn are connected to a source of direct current 8 of the desired potential. The circuit which includes the cathode and anode also 50 contains an inductance 9 which is inductive-

ly related to the inductance 10 in the antenna. The circuit which includes the cathode 3 and the grid 5 contains an inductance 11 which is inductively related to a second inductance 12 in the antenna. The coupling between 9 and 10 is preferably close while that between 11 and 12 may in some cases be made very loose. A battery 13 may be employed for adjusting the normal potential of the grid to a value which is most suitable for the efficient operation of the device. The circuit which comprises the direct current source of supply 8, the inductance 9, the cathode 3, and anode 4, for convenience of description I designate the 60 plate circuit. The circuit which comprises the grid 5, inductance 11, and cathode 3, I designate the grid circuit. Any desired means may be employed for heating the cathode 3 to incandescence. In Fig. 1 I 70 have shown it connected directly across the source of current 8 through a resistance 14 which is made variable to regulate the temperature of the cathode. In the other figures I have shown a local battery 15 for 75 heating the filament.

With the arrangement thus far described continuous electrical waves may be produced in the antenna. When current starts to flow in the plate circuit a potential is induced in 80 coil 10 and in the antenna. This produces a corresponding induced potential in coil 11 and varies the potential of the controlling grid 5. This change in grid potential in turn produces a variation in the current in 85 the plate circuit. When the potential induced in the grid circuit causes the grid to become more negative the current flowing in the plate circuit is decreased while an induced potential which makes the grid more 90 positive increases the current flow in the plate circuit. These variations in the current in the plate circuit produce an alternating current in the antenna, the frequency of 95 which will be the same as the frequency to 100 which the antenna is tuned. The amplitude of the high frequency waves thus produced in the antenna will among other things depend upon the potential of the source of supply 8 and will be constant as 105 long as this potential is constant and other conditions also remain unchanged, but their amplitude will vary in accordance with any variations in the potential supplied to the plate circuit.

In order to vary the amplitude of these waves in accordance with variations in sound waves, I may superimpose upon the constant potential of source 8 potential variations 5 produced by sound waves. In the arrangement shown in Fig. 1 I accomplish this result by including in the plate circuit of electron discharge device 2 the secondary 16 of a transformer, the circuit of the primary 17 of which includes a telephone transmitter 18 with local battery 19. In order that the high frequency component of the current flowing in the plate circuit may not be compelled to pass through secondary 16 and the 15 source of energy 8 condensers 20 and 21 are preferably used to provide shunt paths for the high frequency.

The modification shown in Fig. 2 differs from that shown in Fig. 1 in that instead 20 of superimposing the potential variations in secondary 16 directly upon the plate circuit of device 2 they are amplified by means of a second electron device 22 similar in structure to device 2.

25 In the modification shown in Fig. 3 the direct current source of potential 8 is omitted and the plate circuit of device 2 is supplied only with the potential induced in the secondary of transformer 23. This 30 is of course an alternating potential of the same frequency as the sound waves. When the direction of this potential is such that cathode 3 is positive of course no current will flow in the plate circuit of device 2.

35 As a result the waves transmitted will not be continuous but will be sent out in groups having a frequency equal to that of the sound waves. It is possible to transmit speech by means of waves of this nature 40 though the articulation may not be as perfect as with the other arrangement. This modification however has the advantage over that shown in Figs. 1 and 2, that waves are being supplied to the antenna only while the 45 transmitter 18 is active. At other times the antenna is in condition for receiving signals without disconnecting the transmitting apparatus.

This modification of my invention is 50 described and claimed in my co-pending application, Serial No. 274,288, filed January 31, 1919, which is a continuation in part of the present application.

If desired the coil 12 may be omitted and 55 the coil 11 may be inductively related to coil 10. In most cases however I find that the arrangement shown is preferable as by connecting the circuits in this way the amplitude of the oscillations produced is 60 greater than if coil 11 were coupled to coil 10. This may be due to the fact that the phase relation of the currents in the grid and plate circuits with this arrangement is somewhat different than when coil 11 is 65 directly coupled to coil 10 and that this

difference causes an increase in the amplitude of the oscillations produced.

In the operation of the system which I have described, when the potential induced in the plate circuit by reason of the action 70 of sound waves in the telephone transmitter is such as to cause an increase in the current in the plate circuit there will be a corresponding increase in the current in the antenna. As a result the current induced in 75 the grid circuit will increase correspondingly, the potential upon the grid will be increased, and a further increase in the amplitude of the plate current will be effected thereby. With proper adjustment this cumulative effect may be useful to a large extent 80 in increasing the variations in the amplitude of the waves produced in the antenna. Under some conditions, however, this effect may become so great as to impair the articulation 85 of the speech or other sounds transmitted.

In the operation of my improved system it will usually be found desirable to adjust the potential on the grid 5 so that normally 90 the amplitude of the oscillations produced will be considerably less than the maximum which can be set up in the antenna. With this condition a decrease in the potential in the plate circuit will cause a corresponding decrease in the amplitude of the oscillations 95 set up while an increase in the potential of the plate circuit will produce a corresponding increase in the amplitude of the oscillations.

While I have shown and described three 100 modifications of my invention illustrating its utility for wireless telephony, I do not wish to be limited to the particular arrangements shown as it will be apparent that many variations in the connections used may 105 be made without departing from the scope of the appended claims, and that it may equally well be used for the wireless transmission of other signals than sound waves, or for the transmission of sound or other 110 signals through wired circuits.

What I claim as new and desire to secure by Letters Patent of the United States, is:—

1. The combination in a wireless signaling system of an antenna, means comprising an 115 electron discharge device having plate and grid circuits associated therewith for producing continuous electrical waves of radio frequency in said antenna, and means for supplying a potential which varies at audio frequencies to the plate circuit only of said electron discharge device to vary the amplitude of the waves produced.

2. The combination in a wireless signaling 120 system of an antenna, means comprising an electron discharge device having plate and grid circuits associated therewith for producing continuous electrical waves in said antenna, a source of constant potential in the 125 plate circuit of said electron discharge de-

vice, and means for supplying a variable potential to the plate circuit only of said device in addition to the constant potential to vary the amplitude of the waves produced.

3. The combination in a wireless signaling system of an antenna, means comprising an electron discharge device having plate and grid circuits associated therewith for producing continuous electrical waves in said 10 antenna, a telephone transmitter for producing potential variations which vary in accordance with variations in sound waves, and means for impressing said potential variations upon the plate circuit only of said 15 electron discharge device.

4. The combination in a wireless signaling system of an antenna, an electron discharge device having grid and plate circuits associated therewith, each of said circuits including a coil which is inductively related to a coil in said antenna, and means for supplying a potential which varies at audio frequencies to the plate circuit only of said 20 device.

5. The combination in a wireless signaling system of an antenna, an electron discharge device having grid and plate circuits coupled to separate coils in said antenna and means for impressing a variable potential upon the 30 plate circuit of said device.

6. The combination in a wireless signaling system of an antenna, an electron discharge device for producing oscillations, having grid and plate circuits coupled to separate 35 coils in said antenna, and means for varying the amplitude of the oscillations produced by said electron discharge device.

7. The method of wireless signaling which consists in producing continuous electrical 40 waves in an antenna by means of an electron discharge device having grid and plate circuits associated therewith and varying the amplitude of the waves thus produced by directly applying a variable potential to the 45 plate circuit only of said device.

8. The method which consists in producing continuous electrical waves by means of an electron discharge device having grid and plate circuits associated therewith and varying the amplitude of the waves thus produced by directly applying a variable potential to the plate circuit only of said device.

9. The combination of means comprising an electron discharge device having grid and plate circuits associated therewith for producing continuous electrical waves, and means for supplying a potential which varies at audio frequencies to the plate circuit only of said device to vary the amplitude of the 55 waves produced thereby.

10. The combination of means comprising an electron discharge device having grid and plate circuits associated therewith for producing continuous electrical waves, a 65 source of constant potential in the plate cir-

cuit of said device, and means for supplying a variable potential to the plate circuit only of said device in addition to the constant potential source to vary the amplitude of the waves produced thereby.

11. The combination of means comprising an electron discharge device having grid and plate circuits associated therewith for producing continuous electrical waves, a telephone transmitter for producing potential 75 variations which vary in accordance with variations in sound waves, and means for impressing said potential variations upon the plate circuit only of said electron discharge device.

12. The combination in a wireless signaling system of an antenna, an electron discharge device for producing continuous electrical waves in said antenna comprising a filamentary cathode, a cooperating anode, a discharge controlling grid enclosed in a highly evacuated envelope and grid and plate circuit associated therewith, a source of constant potential in the plate circuit of said device, a telephone transmitter for producing potential variations which vary in accordance with variations in sound waves, and means for impressing said potential variations upon the plate circuit only of said 85 device.

13. The combination in a signaling system of means comprising an electron discharge device having an incandescent cathode, an anode and a grid for producing continuous electrical waves, a circuit between cathode and anode and means for impressing upon a portion of said circuit through which only anode currents flow a variable potential for varying the amplitude of the waves produced.

14. The combination of an oscillation circuit with means comprising an electron discharge device having plate and grid circuits associated therewith for producing continuous electrical waves of high frequency in said oscillation circuit, and means for supplying a potential which varies at audio frequencies to the plate circuit only of said electron discharge device to vary the amplitude of the waves produced.

15. The combination of an oscillation circuit with means comprising an electron discharge device having plate and grid circuits associated therewith for producing continuous electrical waves in said oscillation circuit, a source of constant potential in the plate circuit of said electron discharge device, and means for supplying a variable potential to the plate circuit only of said device in addition to the constant potential to vary the amplitude of the waves produced.

16. The combination of an oscillation circuit with means comprising an electron discharge device having plate and grid cir-

cuits associated therewith for producing continuous electrical waves in said oscillation circuit, a telephone transmitter for producing potential variations which vary in accordance with variations in sound waves, and means for impressing said potential variations upon the plate circuit only of said electron discharge device.

17. The combination of an oscillating circuit with an electron discharge device having grid and plate circuits associated therewith, each of said circuits having an inductance coupling to said oscillating circuit, and means for supplying a potential which varies at audio frequencies to the plate circuit only of said device.

18. The method of signaling which comprises producing continuous electrical waves in an oscillation circuit by means of an electron discharge device having plate and grid circuits associated therewith, and varying the amplitude of the waves thus produced by directly applying a variable potential to the plate circuit only of said device.

19. The combination of an oscillation circuit with an electron discharge device for producing continuous electrical waves in said oscillation circuit, comprising a filamentary cathode, a cooperating anode, a discharge controlling grid enclosed in a highly

evacuated envelope, and grid and plate circuits associated therewith, a source of constant potential in the plate circuit of said device, a telephone transmitter for producing potential variations which vary in accordance with variations in sound waves, and means for impressing said potential variations upon the plate circuit only of said device.

20. The method of modulating high frequency continuous electrical oscillations produced by an electron discharge device having an electron emitting cathode, an anode and a grid which consists in applying a variable potential to the anode and thereby producing substantially all of the desired amplitude variation.

21. The method of modulating high frequency continuous electrical oscillations produced by an electron discharge device having an electron emitting cathode, an anode and a grid, which consists in causing the potential of the anode to vary in accordance with the desired modulation and thereby producing substantially all of the desired amplitude variation.

In witness whereof, I have hereunto set my hand this 20th day of August, 1915.

WILLIAM C. WHITE.
